Peter J. Wilson,
By Charles Turner Brown,
Atty.

UNITED STATES PATENT OFFICE.

PETER J. WILSON, OF CHICAGO, ILLINOIS.

TOY.

1,253,449.

Specification of Letters Patent. Patented Jan. 15, 1918.

Application filed February 10, 1917. Serial No. 147,781.

To all whom it may concern:

Be it known that I, PETER J. WILSON, a citizen of the United States, and a resident of Chicago, in the county of Cook and State 5 of Illinois, have invented certain new and useful Improvements in a Toy for Children, of which the following is a specification.

This invention relates to the class or kind of toys which requires physical exercise on 10 the part of a child playing therewith and which promotes such exercise by the interest and attention aroused in the child by the operation and result of the play.

The objects of the invention are to obtain 15 a toy of the kind named which is novel in character; which is durable and will withstand rough or hard usage from a child; which is not liable to cause injury to a child playing with it; which is economically 20 made; and which will not occupy any considerable space when housed.

Additional objects are disclosed by the specification and claims.

I have illustrated a toy embodying this 25 invention in the drawing accompanying and forming a part hereof, in which—

Figure 1 is a rear elevation;

Fig. 2 a side elevation; and

Fig. 3 a rear elevation of a part of the 30 frame of the toy, showing a modification of said frame.

A reference character applied to designate a given part indicates said part throughout the several figures of the drawing wherever 35 the same appears.

The toy comprises a frame (A), provided with a horizontal axle (B), and vertical axles or shafts (C, C'). On the horizontal axle wheels (D, D'), which support or carry 40 the frame A are rotatably mounted. On the vertical shafts there are rotatably mounted cages or frames (E, E'), the lower ends of which (indicated by letters e) rest on the peripheral face (d) of carrying wheels D. Supported by a loose bearing at the upper 45 ends of the vertical shafts or axles C, C', is the rotatably mounted shaft F, and on said shaft there are rigidly secured the fan wheel H and the wheels G, G'. Said wheels G, G' 50 rest on the upper side of the ends e', of the respective cages E, E'. Fan wheel H is in appearance a propeller wheel.

The frame A which is illustrated in the drawing is made of wire; but the making 55 it all of wire is not an essential requirement in the concrete embodiment of the inven-

tion. To make the frame A, which is illustrated, a wire of sufficient length and diameter is taken, and starting at one end thereof (say a), it is extended to bend b, where it 60 is bent over on itself and wound or twisted to obtain the part b' of axle B, on which the hub d' of carrying wheel D is mounted. The wind or twist is continued to bend b'' and by said bend the vertical part a'' of 65 the wire is obtained, which is extended to a return bend. A wind or twist of the parallel strands which are obtained by the return bend is made, similar to the wind or twist by means of which the part b' of axle 70 B is obtained, and thereby the vertical shaft C, on which the cage or frame E is rotatably mounted, is obtained. At the lower end of shaft C the bend C' is made, and at J an additional bend is made. From the bend J 75 the above described bends and twists are repeated, but in reverse order, to obtain the vertical shaft C' and a duplicate part b' of axle B, thus bringing the end a' of the wire adjacent to end a, and said ends are then 80 secured together by winding or twisting. Wheel D' is mounted on the duplicate part b' of axle B.

An additional piece of wire is wound around part b' of axle B, as at K, K, and 85 around the first named wire adjacent to bend J, as at k, k, to complete the frame, when required.

The frame or cages E, E', respectively comprise the ends e, e', hereinbefore recited, 90 and the spacing members e'', which are illustrated as made of wire.

The carrying wheels D, D', are illustrated as being the ordinary wire spoked and rubber tired wheels used on small vehicles, and 95 well known in the market.

The ends of the frames or cages E, E' and the bearing edges of the wheels G, G', are illustrated as beveled, to obviate friction of connecting faces.

L is the handle or pole of the device, and is provided with slot l at the end thereof, which is engageable to frame A. To attach handle L to frame A the wire of the frame A which is positioned at bend J, and the 100 part of the additional wire between the winding at K, K is inserted in slot or recess l, and to retain said handle in said attachment a cotter pin M, (see Fig. 2) is inserted 105 in suitably positioned holes therefor in said handle.

In the modification which is illustrated in

Fig. 3 the parts of the first named wire which are adjacent to ends a, a' are wound or turned around the additional piece of wire, (as at N, Fig. 3), instead of being joined, (as in Fig. 1).

The operation of the device is, upon drawing or pushing it upon a floor or pavement wheels D, D' will turn and the frames or cages E, E' which rest on the peripheries 10 of said wheels are thereby turned; and the turning of said frames or cages turns the wheels G, G' which rest on the upper ends of said frames or cages. The wheel H is turned with shaft F, which is turned by 15 wheels G, G'.

The wheels D, D' and frames or cages E, E' are retained on their respective axles and shafts by spreading the bent wire adjacent to the bends at the ends of said axles 20 and shafts.

I claim:

1. A frame, comprising a horizontal member and vertical members, said vertical members consisting of wire bent to obtain parallel strands and said strands wound together, in combination with carrying wheels 25 rotatably mounted on said frame, cages ro-

tatably mounted on said vertical members and arranged to be rotated by the rotation of said carrying wheels, a loosely mounted 30 rotatable shaft, the ends whereof are inserted in said bends, wheels and a fan rigidly secured on said shaft, said wheels arranged to rest on and be turned by the turning of said cages, and a handle attached to said 35 frame.

2. A frame consisting of wire provided with bends and with the parts of said wire adjacent to said bends joined by twisting, and provided with additional bends to position 40 said twisted portions of the wire at substantially right angles, to form the ends of a horizontal axle and vertical shafts, carrying wheels rotatably mounted on said ends and frames rotatably mounted on said shafts, 45 an additional rotatably mounted shaft, wheels and a fan rigidly secured on said additional shaft, said wheels arranged to connect with the upper ends of said frames and to be turned by the turning of said frames. 50

PETER J. WILSON.

In the presence of—

CHARLES TURNER BROWN,
J. SCUDDER.
